UNITED STATES PATENT OFFICE.

GEORGE C. HICKS, JR., OF CONNERSVILLE, INDIANA.

SHAFT-COUPING.

1,219,943.

Specification of Letters Patent.

Patented Mar. 20, 1917.

Application filed December 13, 1916. Serial No. 136,636.

To all whom it may concern:

Be it known that I, GEORGE C. HICKS, Jr., a citizen of the United States, residing at Connersville, Fayette county, Indiana, have 5 invented certain new and useful Improvements in Shaft-Couplings, of which the following is a specification.

This invention pertains to shaft-couplings of the articulated class and will be readily 10 understood from the following description taken in connection with the accompanying drawing in which:—

Figure 1 is an elevation of a coupling exemplifying my invention, parts appearing 15 in vertical section in the plane of line *c* of Figs. 2 and 3:

Fig. 2 an elevation of the same, partly in vertical section, in the plane of line *a* of Fig. 1:

20 Fig. 3 a plan of a pair of the driving pins, the spring appearing in section in the plane of line *b* of Figs. 1, 2 and 4:

Fig. 4 a vertical section of the driving- 25 pins in the plane of line *c* of Figs. 2 and 3: and

Fig. 5 an elevation of a modified form of spring band. A diversity of scales is employed in the drawing.

In the drawing:—

30 1, indicates one of the flanges of a flanged coupling adapted to be secured on the end of a shaft:

2, a similar flange to be secured to the companion shaft, the contiguous faces of the 35 two flanges being spaced apart, it being understood that these flanges may be simple flanges as illustrated, or that either or both of them may form or be embodied in members secured to shafts, as pulleys, gears, etc.:

40 3, two circumferential series of pins, one series in each of the flanges, the pins being secured rigidly in their flanges, by any suitable means, and projecting from their flanges across the space between the flanges, 45 the inner ends of the pins of one series overlapping the inner ends of the pins of the other series:

4, the overlapping ends of the pins, illustrated as being halved so as to present flat 50 surfaces to each other:

5, a spring band or link encircling the overlapping ends of each pair of pins, this band being a spiral spring formed of a flat strip coiled up into a hoop of a size to en-

compass the overlapping ends of its pair of 55 pins: and

6, a cushion, as, of leather, secured between the contiguous flat faces of each pair of pins.

With the overlapping ends of the pins 60 halved as illustrated, the two ends conjointly form a cylindrical surface for the reception of the spring band. If the pins of one series drive the pins of the other series by pushing contact, cushioned by the leather, then the 65 spring bands are, for the instant, without office, regardless of whether the spring bands fit their pairs of pins snugly or loosely. But if, while one set of pins is driving the other set by pushing engagement, the driven 70 set seeks to run ahead, as by retardation of the velocity of the driving means the pins will separate from each other, but such separation will be elastically resisted by the spring bands whose interiors become elongated as the pins separate. The spring bands, of course, become less yielding as the pins separate and they should be of such 75 elastic strength as to withstand any strain that may be put upon them in the proper 80 operation of the coupling. If, now, the pins in advance be the driving pins, then the driving of the other set of pins will be effected by traction through the medium of the spring bands which yield and elongate 85 as the pins of the pairs separate. In this case the driving of one shaft by the other is effected through an elastic medium, the leathers softening the effect in backlash, while in the case first mentioned, the driving is positive, 90 except as influenced by the leathers, and angular advance of the driving-member of the coupling is permitted to take place elastically through the medium of the spring bands. Aside from the angular elasticity 95 of the system there is manifestly present a capacity for compensating for any reasonable lack of alinement between the two shafts. The construction is not only highly 100 satisfactory in operation but it is very simple and economical of production as the spring bands and the overlapping ends of the pins do not necessarily require any finishing or accurate relative sizing.

When the bands are formed as coiled 105 springs, as illustrated in Fig. 4, there is not present an endless tension element. In other words, looking at Fig. 4, there would be no

limit to the degree of separation of the pins as the spring could uncoil completely. In the modification illustrated in Fig. 5, the outer member 7 of the band is endless, while 5 flexible, and the spring characteristic is given to the band by spring leaves 8 secured to the band. Such a band will behave normally the same as the band in coiled spring form, the band elongating as the pins separate, but the degree of separation of the pins 10 is limited by the tensional strength of the outer member 7.

Attention should be called to the fact that, taking the case of spring bands formed of 15 spiral coils, the driving strains tending to elongate the bands are resisted by the frictional contact of the members of the coils. In other words, the layers of the coils must slip upon each other, and the friction of this 20 slipping brings about a sort of dash-pot action tending to prevent the bands from elongating under sudden impulsive strains, thus reducing the sharpness of the elastic action.

25 I claim:—

1. A coupling comprising, two rotatable members with a substantially common axis and with their contiguous faces spaced apart, a series of projections carried by each 30 of the members and extending toward the contiguous face of the other member, the extending ends of the projections of one series overlapping the extending ends of the projections of the other series, and an 35 elastic link encompassing each pair of overlapping projections and adapted to permit the projections of one series to engage with or separate from the projections of the other series, combined substantially as set forth.

40 2. A coupling comprising, two rotatable members with a substantially common axis and with their contiguous faces spaced apart, a series of projections carried by each 45 of the members and extending toward the contiguous face of the other member, the extending ends of the projections of one series overlapping the extending ends of the projections of the other series, a cushion disposed between the overlapping projections of each pair, and an elastic link encompassing each pair of overlapping projections and adapted to permit the projections of 50

one series to engage with or separate from the projections of the other series, combined substantially as set forth. 55

3. A coupling comprising, two rotatable members with a substantially common axis and with their contiguous faces spaced apart, a series of pins rigidly secured in each of the members and having ends extending toward the contiguous face of the other member, the extending ends of one series of pins overlapping the extending ends of the other series, and an elastic link encompassing each pair of overlapping pin-ends and adapted to permit the pins of one series to engage with or separate from the pin-ends of the other series, combined substantially as set forth. 60 65

4. A coupling comprising, two rotatable members with a substantially common axis and with their contiguous faces spaced apart, a series of cylindrical pins rigidly secured in each of the members and having semi-cylindrical ends extending toward the 70 contiguous face of the other member, the flat faces of the semi-cylindrical ends of one series of pins overlapping the flat faces of the semi-cylindrical ends of the other series, and an elastic link encompassing each pair 75 of overlapping pin-ends and adapted to permit the pins of one series to engage with or separate from the pin-ends of the other series, combined substantially as set forth. 80

5. A coupling comprising, two rotatable 85 members with a substantially common axis and with their contiguous faces spaced apart, a series of cylindrical pins rigidly secured in each of the members and having semi-cylindrical ends extending toward the 90 contiguous face of the other member, the flat faces of the semi-cylindrical ends of one series of pins overlapping the flat faces of the semi-cylindrical ends of the other series, and a coiled spring band encompassing each 95 pair of overlapping pin-ends and adapted to permit the pins of one series to engage with or separate from the pin-ends of the other series, combined substantially as set forth.
